UNITED STATES PATENT OFFICE.

THOMAS R. HARTELL AND JOHN LETCHWORTH, OF PHILADELPHIA, PA.

DESIGN FOR MEDALS.

Specification forming part of Design No. **7,828**, dated November 3, 1874; application filed October 7, 1874.
[Term of Patent 3½ years.]

To all whom it may concern:

Be it known that we, THOMAS R. HARTELL and JOHN LETCHWORTH, of Philadelphia, in the county of Philadelphia and State of Pennsylvania, have invented a certain Design for Medals; and we do hereby declare the following to be a full, clear, and exact description of the design, reference being had to the accompanying fac-simile which forms part of this specification, illustrating a perspective view of the Centennial Exposition buildings.

Our design for a medal consists of a view of the Centennial buildings of the Exposition to be held in Philadelphia, State of Pennsylvania, in the year 1876, as shown in the accompanying photograph.

The figure in the accompanying fac-simile is a perspective view of the Centennial buildings, which design is applied to one side or both sides of a medal, in any suitable manner.

What we claim is—

The design for a medal, shown in the accompanying photograph.

In testimony that we claim the foregoing we have hereunto set our hands this 3d day of September, 1874.

THOS. R. HARTELL.

JOHN LETCHWORTH.
